(57) **CLAIM**

The ornamental design for a combined electrical switch with mounting plate, as shown and described.

DESCRIPTION

1.-2. Combined electrical switch with mounting plate

2.1 : Perspective

2.2 : Front

2.3 : Left

2.4 : Back

2.5 : Top

2.6 : Bottom

2.7 : Perspective

In the reproductions, the broken lines are for the purpose of illustrating portions of the combined electrical switch with mounting plate that forms no part of the claimed design.
